J. E. STEWARD

RAIL JOINT

Original Filed March 14, 1923

INVENTOR

Joseph E. Steward
BY
Adrian F. Fisher
ATTORNEY

UNITED STATES PATENT OFFICE.

JOSEPH ELIAS STEWARD, OF PRINCE GEORGE, BRITISH COLUMBIA, CANADA.

RAIL JOINT.

Application filed March 14, 1923, Serial No. 625,021. Renewed October 29, 1924.

To all whom it may concern:

Be it known that I, JOSEPH ELIAS STEWARD, a subject of the King of Great Britain, residing in the city of Prince George, British Columbia, Dominion of Canada, have invented new and useful Improvements in Rail Joints, of which the following is a specification, reference being had to the accompanying drawings.

10 This invention is a rail joint for connecting the abutting ends of two railway rails, and the object is to provide a joint which will do away with the necessity of fish plates and bolts.

15 Figure 1 is a side elevation of two abutting rails connected in accordance with this invention.

Figure 2 is a side elevation of the two rail ends disconnected.

20 Figure 3 is a top view of the two rail ends disconnected.

Figure 4 is a bottom view of the two rail ends disconnected.

25 Figure 5 is an end view of the two rail ends disconnected.

In carrying out the invention the ends of the two abutting rails 1 and 2 are thickened at the webs 3 which connect the balls 4 and feet 5 of the rails, as shown at 6.

30 The extremity of the rail 1 is fashioned wedge-like as shown at 7, with a central extension or flat key 8 extending up beyond the general wedge, and back of this wedge-like portion the rail 1 is cut away to a flat surface 9 below the ball of the rail, and an elongated key slot 10 is formed therein. Back of this slot 10 the ball of the rail is cut away diagonally as shown at 11. The end of the other rail 2 is fashioned comple-

40 mentary to the formations at the end of the rail 1, and includes a V-shaped recess 12 to fit over the wedge portions 7 and 8 of the rail 1, the center of the recess 12 being cut deeper as shown to form an elongated

45 key-slot 13 adapted to engage the key 8 of the rail 1. The ball of the rail 2 is left outstanding and extended beyond the V-shaped portion to form a filler strip 14 for the cut away top portion of the rail 1, and similarly

50 the end of the filler strip 14 is cut away diagonally at 11 to meet the diagonal ending 11 of the ball of the rail 1. A flat key 15 is left at the under side of the strip 14 to engage the key slot 10. The rail ends are

55 locked against vertical play by piercing bolt holes 17 through the side walls of the

key slot 13 of the rail 2 and an aligned bolt slot 18 through the key 8 of the rail 1, and passing a bolt 16 through these apertures. The slot 18 allows for the longitudinal play of the rail ends without any strain in this direction on the bolt. Thus the longitudinal stress is taken care of by the interlocking keyed and recessed formation of the rail ends, while the bolt acts to check the vertical play, if any. This completes the joint, the two parts of which are complementary one to the other and which is assembled by vertical relative movement of the rail ends, and it is evident that they will so interlock that no cross bolts are necessary, the rails being held in place by the usual spikes only.

While I have herein described a certain specific method of constructing and assembling the elements of my invention, it is understood the same may be varied in minor details, not departing from the spirit of my invention as defined in the appended claims.

I claim:

1. A rail joint for two abutting rails, comprising thickened webs at the ends of the rails, the extremity of one rail being fashioned wedge-like with a central key up-standing thereon, the rail being cut away to a flat surface below the ball of the rail and back of the said wedge portion and diagonally at the ball of the rail, and a key slot being formed in the said flat surface; and the extremity of the other rail being formed to exactly meet the formations at the end of the first mentioned rail and so as to fit thereto complementarily.

2. A rail joint for two abutting rails, comprising thickened webs at the ends of the rails, the extremity of one rail being fashioned wedge-like with a central key up-standing thereon, the rail being cut away to a flat surface below the ball of the rail and back of the said wedge portion and diagonally at the ball of the rail, and a key slot being formed in the said flat surface; the extremity of the other rail being formed to exactly meet the formations at the end of the first mentioned rail and so as to fit thereto complementarily; and means for locking the rail ends against vertical play.

3. A rail joint for two abutting rails, comprising thickened webs at the ends of the rails, the extremity of one rail being fashioned wedge-like with a central key up-standing thereon, having a bolt slot there-

through; the rail being cut away to a flat surface below the ball of the rail and back of the said wedge portion and diagonally at the ball of the rail, and a key slot being formed in the said flat surface; the extremity of the other rail being formed to exactly meet the formations at the end of the first mentioned rail and so as to fit

thereto complementarily, including a key slot for the said central key of the first named rail, with bolt holes formed through the side walls thereof in alignment with the said bolt slot; and a bolt passed through the said aligned apertures.

JOSEPH E. STEWARD.
